FIELD ENGINEERING CO., OF CHICAGO, ILLINOIS, A CORPORATION OF ILLINOIS.

OIL BURNER.

Application filed April 20, 1925. Serial No. 24,422.

This invention relates to improvements in oil burners.

The main objects of the invention are:

First, to provide an improved oil burner which may be easily installed in furnaces and in other relations where desired, and which is very efficient.

Second, to provide an improved oil burner which is effective and does not require the use of motor power.

Third, to provide an improved burner adapted for the burning of heavy oils and distillate which is substantially smokeless and may be readily freed from any carbon or dirt, which may be collected therein.

Fourth, to provide an improved oil burner having these advantages which is economical in its parts and may be quickly installed in furnaces of the type now in quite common use.

Fifth, to provide in connection with the burner an automatic draft regulator.

Objects pertaining to details and economies of our improvements will definitely appear from the detailed description to follow.

We accomplish the objects of our invention by the devices and means described in the following specification. The invention is clearly defined and pointed out in the claims.

A structure embodying the features of our invention is clearly illustrated in the accompanying drawing forming a part of this application, in which:

Fig. I is a fragmentary side elevation of a hot air furnace having our improved oil burner installed therein, the furnace being shown in conventional form for the purpose of illustrating the matter of installation.

Fig. II is a detail vertical section on a line corresponding to line 2—2 of Figs. I and III.

Fig. III is a detail view mainly in horizontal section on a line corresponding to line 3—3 of Fig. II.

Fig. IV is a side view of one of the inner parts.

Fig. V is a detail view partially in vertical section of the atomizing head.

Fig. VI is a fragmentary section on a line corresponding to line 6—6 of Fig. II showing details of the atomizing head spindle bearings.

Fig. VII is a detail view partially in section showing details of the fuel nozzles.

Fig. VIII is a top view of the draft regulator.

Fig. IX is a detail section of the draft regulator on a line corresponding to line 9—9 of Fig. VIII.

Fig. X is a detail section of the draft regulator on a line corresponding to line 10—10 of Fig. VIII.

In the drawing the sectional views are taken looking in the direction of the little arrows at the ends of the section lines and similar numerals of reference indicate similar parts throughout the several views.

Referring to the drawing, 1 represents the hot air casing of the furnace, 2 the body thereof, 3 the fire pot and 4 the ashpit. These parts are shown conventionally.

Our improved burner comprises a body consisting of a bottom member 5 having an inwardly converging intermediate portion 6 and a bottom portion 7 which is open with the exception of the cross piece or spider. 75 The top body member 9 is provided with an outer wall 10 resting upon the upper edge of the bottom body member 5 and supported thereby, and an inner wall 11 depending within and in spaced relation to the outer wall. The inner wall has opposed openings 12 therein with spaced lugs 13 above the openings. The purpose of the openings and lugs will appear as the description proceeds.

The top body member has opposed enlargements 9' to receive the fuel supply pipe coupling members 14. The branches 15 from the fuel supply pipe 16 are connected to the lower ends of these coupling members.

Centrally supported within the bottom body member is an inner wall bottom member 17 which is supported in spaced relation to the outer bottom member by the lugs 18. The inner wall bottom member is shouldered at 19 to receive the lugs and is clamped in 90 position on the lugs by means of the screw 20.

This inner wall bottom member has a flange 21 disposed in concentric relation to the side wall of the bottom member providing an annular fuel drain trough 22. This drain trough is provided with a drain pipe 24 delivering to the receptacle 25. The inner wall bottom member 17 also has a central air opening 26 therein.

An annular shaker member 27 is mounted 105 upon the inner wall bottom member to constitute an inner wall member. This shaker member has a flange 28 on its lower edge projecting into the member 17, this flange having slot-like openings 29 therein adapted 110

when the shaker member is elevated to open to the space at the outside of the inner wall.

This shaker member 27 is provided with a plurality of inclined supporting lugs 30 adapted to rest on the supporting rollers 31 on the inside of the bottom body member. Pins 32 project over these lugs 30 holding the shaker member upon its supporting rollers. The shaker member is thus supported for 10 rotative or vertical movement and is raised upon the rotation thereof to open the ports 29. A lever 33 pivoted at 34 engages between the lugs 35 for oscillating the shaker member.

The top inner wall member 36 rests upon 15 the upper edge of the shaker member and is supported centrally thereof by means of the fingers 37. This allows for the rotative movement of the shaker member.

These inner wall members 17, 27 and 36 20 constitute an inner wall and coact with the body members and the combustion chamber wall to provide a return air passage delivering into the lower end of the combustion chamber. A cover plate 38 of general coni- 25 cal form is carried by the flange 21 of the member 17, the cover plate having a flange 39 embracing the flange 21.

A pair of annular clearance members 40 and 41 are arranged in superimposed relation 30 upon the flange 28 of the member 27 coacting therewith and with the cover plate 38 which rests upon the clearance member 40 to provide a cover for the drain trough, at the same time allowing any surplus liquid fuel to flow 35 into the drain trough to be discharged as described. Any dirt, carbon or soot falling upon the cover plate or from the combustion chamber is directed outwardly upon the clearance members and through the openings 40 upon the actuation of the shaker. These 45 clearance members are supported for independent rotative movement and the return of the shaker to its initial position, owing to the fact that the members merely rest upon each other and their inertia and difference 50 in friction between them, tends to cause these members to rotate relative to each other and to the flange 28, thereby freeing the same of any collection of carbon or dirt and jarring it loose so that it is discharged through the openings 29.

We provide a spray head consisting of the head member 42 having depending lugs 43 upon which the radial arms 44 are carried, 55 these arms 44 having an annular atomizing plate 45 mounted thereon. The plate has fan-like blades 46 formed in its outer edge. The outer ends 47 of the arms 44 are turned upwardly to support the rim 48 in the plane of 60 the atomizing plate.

A baffle plate 49 is mounted upon the head member 42 so that air flowing through the atomizing plate is directed outwardly by this baffle plate. The atomizing head is supported by the spindle 50 having a notch 51

in its upper edge adapted to engage the cross pin 52 in the tubular shank 53 of the atomizing head, thereby rotatably connecting the head to the spindle but permitting its being lifted from the spindle as occasion requires. 70

The spindle is provided with an end bearing member 54 having a spherically curved end portion coacting with the bearing block 55 in the tubular bearing member 56 which is threaded into the cross member 8 at the lower end of the burner body. The cover plate 38 and the inner wall bottom member 17 coact to form a bearing chamber 57 for the spindle bearing 58 which is mounted on a cross piece 59 within the chamber. The cover plate 38 has a central opening 60 alined with the opening 26 so that a current of air is caused to flow through this bearing chamber preventing overheating of the bearing 58. 80

To further protect the bearing 58 we provide a conical guard 61 having a tubular portion 62 embracing the spindle and projecting through the opening 60, thereby more effectively directing the air across the bearing 58 and further shielding it from the heat in the 90 combustion chamber.

The fan propeller 63 is mounted upon the spindle within the reduced portion 7 of the body so that it is subjected to the current of air which is set up or induced by the draft 95 of the combustion chamber, and this also causes a current of air to flow around the lower bearing, thereby preventing its becoming overheated. The lower bearing is provided with a lubricating connection 64 into 100 which the lubricant may be introduced, the bearing having a drain opening 65 for the escape of excess lubricant. The bearing 58 is of self-lubricating material and requires no lubrication. 105

The fuel is delivered to the atomizing head by fuel nozzles comprising the delivery tubes 67 mounted in a downwardly inclined relation on the couplings 14 and the nozzle tubes 68 which have sliding engagement with the tubes 67. These nozzles 68 have downwardly directed delivery tips 69. 110

To prevent the delivery nozzles becoming overheated we provide insulating or protecting cases 70 having enlargements 71 in the upper ends thereof and discharge openings 72 at the lower ends thereof. These enlargements have lugs 73 adapted to be engaged between the lugs 13 on the combustion chamber walls for positioning the nozzles, at the same time permitting the easy removal thereof by pushing the nozzle inwardly to disengage from the lugs, turning to an inverted position, and drawing through the openings 12. 115

In the event of the nozzle tips 69 becoming 125 clogged the fuel will back up around the discharge tube into the protective casing and be discharged through the openings 72. In the event of the burner becoming extinguished inadvertently or otherwise an excess 130

of fuel being delivered, the fuel drips down upon the cover plate and clearance members into the trough and is discharged through the drain conduit 24 to the receptacle 25 which is provided with a float 74 controlling a valve 75 for the fuel feed pipe 16, thereby cutting off the flow of fuel.

In Fig. I we have, as stated, illustrated our burner as installed in a common type of hot air furnace, the grate being removed and the burner inserted with a plate 76 embracing the same. The firepot of the furnace is filled in above this plate with sand or other suitable filler 77 substantially sealing the burner so 15 that air flowing through the furnace is directed through the burner.

We preferably in this connection provide an automatic draft regulator in connection with the smoke flue 78. This comprises a 20 damper plate 79 having an opening 80 therein. The damper 81 is pivoted at 82 to swing downwardly in closing. The damper is provided with a counterbalancing arm 83 threaded to receive the counterweight 84, the hole 25 in the counterweight being preferably eccentrically disposed so that rotation by jarring or vibration is prevented. In use the counterweight is adjusted to normally hold the damper in the desired position to secure the 30 required draft through the burner. Any excess of draft due to atmospheric conditions will cause the damper to open further, thereby maintaining a substantially uniform draft of air through the burner.

35 By this arrangement of parts a natural draft is set up through the burner, that is no motor air driving or blast fan is required, and when the draft regulator is employed the structure is automatic. The damper to the 40 furnace, being suitably controlled, controls the burner.

By avoiding the necessity of motors the liability of the structure becoming inoperative in use is greatly reduced and a more or less 45 noisy element is eliminated. By delivering a quantity of cold air through the central conduit, the amount of cold air being automatically regulated by the draft through the burner which is in turn regulated by the controlling damper, the walls of the combustion chamber are prevented from becoming overheated, and, also, the atomizing head is 50 prevented from becoming overheated. The balance or proportion of the cold air being once determined remains substantially constant.

55 Our improved burner requires little attention in use as the atomizing head is automatically driven without the aid of external force or motors requiring power other than that induced by the draft of air. The burner is readily cleaned from any accumulation of carbon, dirt or the like and may be easily regulated as desired.

We have illustrated and described our improvements in an embodiment which we have

found very practical. We have not attempted to illustrate or describe various modifications or adaptations as we believe this disclosure will enable those skilled in the art to embody our improvements as may be desired.

Having thus described our invention what we claim as new and desire to secure by Letters Patent is:

1. In an oil burner, the combination of a 75 body open at the bottom for the ingress of air and having a combustion chamber open at the top and bottom disposed centrally therein, an inner wall mounted within said body in spaced relation to the walls thereof and to 80 the wall of said combustion chamber providing a return air passage open at the bottom and surrounding said combustion chamber and delivering to the bottom thereof, an atomizing head disposed within the combustion chamber adjacent the bottom thereof, 85 means for delivering fuel to said head, a spindle for said head, a restricted air delivery conduit open at the bottom and delivering centrally below said atomizing head 90 whereby the combustion chamber walls and head are prevented from becoming overheated and a natural draft secured, and a driving propeller on said spindle disposed in said body below said central air passage to be 95 driven by air passing therethrough.

2. In an oil burner, the combination of a body open at the bottom for the ingress of air and having a combustion chamber open at the top and bottom disposed centrally 100 therein, an inner wall mounted within said body in spaced relation to the walls thereof and to the wall of said combustion chamber providing an air passage open at the bottom and surrounding said combustion chamber 105 and delivering to the bottom thereof, an atomizing head rotatably mounted within the combustion chamber, means for delivering fuel to said head, a restricted cold air delivery conduit open at the bottom and delivering centrally below said atomizing head 110 whereby the combustion chamber walls and atomizing head are prevented from becoming overheated and a natural draft secured, and a driving propeller on said spindle disposed in said body below said central air passage 115 to be driven by air passing therethrough.

3. In an oil burner, the combination of a bottom body member open at the top and bottom, a top body member superimposed thereon and having a concentric combustion chamber wall depending from its upper edge providing a combustion chamber open at the top and bottom, an inner wall bottom member mounted centrally within said bottom body member and having an annular flange spaced from its side wall providing an annular fuel drain trough, a cover plate resting on said flange of said bottom wall member, an annular shaker member constituting an inter- 120 125 130

- mediate inner wall member superimposed on said bottom wall member and having a flange with openings therein depending within said bottom wall member so that said openings are 5 closed when the shaker member is in its normal position, said shaker member having spirally disposed supporting lugs thereon, said bottom body member having coacting supports whereby said shaker member is supported for rotary and vertical movement, means for actuating said shaker member, an annular baffle wall member superimposed on said shaker member in concentric relation to said combustion chamber wall and constituting 10 a top inner wall member, said body, combustion chamber wall and inner wall members coacting to provide a return air passage delivering to the bottom of said combustion chamber, an annular clearing member interposed between said shaker member flange and said cover for independent rotary movement and coacting therewith to provide a cover for said fuel trough permitting the passage of fuel thereto, and a fuel feed means 15 disposed in said combustion chamber.
4. In an oil burner, the combination of a bottom body member open at the top and bottom, a top body member superimposed thereon and having a concentric combustion chamber wall depending from its upper edge providing a combustion chamber open at the top and bottom, an inner wall bottom member mounted centrally within said bottom body member and provided with an annular fuel 20 drain trough, an annular shaker member constituting an intermediate inner wall member superimposed on said bottom wall member for rotary and vertical movement and having a flange with openings therein depending within said bottom wall member so that said openings are closed when the shaker member is in its normal position, means for actuating said shaker member, an annular baffle wall member superimposed on said shaker member in concentric relation to said combustion chamber wall and constituting a 25 top inner wall member, said body, combustion chamber wall and inner wall members coacting to provide a return air passage delivering to the bottom of said combustion chamber, and a fuel feed means disposed within said combustion chamber.
5. In an oil burner, the combination of a bottom body member open at the top and bottom, a top body member superimposed thereon and having a concentric combustion chamber wall depending from its upper edge providing a combustion chamber open at the top and bottom, an inner wall bottom member mounted centrally within said bottom body member and provided with an annular shaker member superimposed on said bottom wall member for rotary and vertical movement and having a flange with openings therein depending within said bottom wall member so that said openings are closed when the shaker member is in its normal position, means for actuating said shaker member, an annular baffle wall member superimposed on said shaker member in concentric relation to said combustion chamber wall and constituting a top inner wall member, said body, combustion chamber wall and inner wall members coacting to provide a return air passage delivering to the bottom of said combustion chamber, a fuel feed means disposed within said combustion chamber, a plate arranged below said fuel feed means to project over said drain trough, and a clearing member interposed between said shaker member flange and said plate for independent rotary movement.
6. In an oil burner, the combination of a bottom body member open at the top and bottom, a top body member superimposed thereon and having a concentric combustion chamber wall depending from its upper edge providing a combustion chamber open at the top and bottom, an inner wall bottom member mounted centrally within said bottom body member, an annular shaker member constituting an intermediate inner wall member superimposed on said bottom wall member for rotary and vertical movement and having a flange with openings therein depending within said bottom wall member so that said openings are closed when the shaker member is in its normal position, means for actuating said shaker member, an annular baffle wall member superimposed on said shaker member in concentric relation to said combustion chamber wall and constituting a top inner wall member, said body, combustion chamber wall and inner wall members coacting to provide a return air passage delivering to the bottom of said combustion chamber, and a fuel feed means disposed within said combustion chamber.
7. In an oil burner, the combination of a bottom body member open at the top and bottom, a top body member superimposed thereon and having a concentric combustion chamber wall depending from its upper edge providing a combustion chamber open at the top and bottom, an inner wall bottom member mounted centrally within said bottom body member, an annular shaker member constituting an intermediate inner wall member superimposed on said bottom wall member for rotary and vertical movement and having a flange with openings therein depending within said bottom wall member so that said openings are closed when the shaker member is in its normal position, means for actuating said shaker member, an annular baffle wall member superimposed on said shaker member in concentric relation to said combustion chamber wall and constituting a top inner wall member, said body, combustion chamber wall and inner wall members coacting to provide a return air passage delivering to the bottom of said combustion chamber, and a fuel feed means disposed within said combustion chamber.

- its normal position, means for actuating said shaker member, an annular baffle wall member superimposed on said shaker member in concentric relation to said combustion chamber wall and constituting a top inner wall member, said body, combustion chamber wall and inner wall members coacting to provide a return air passage delivering to the bottom of said combustion chamber, a fuel feed means 5 disposed within said combustion chamber, and a conical plate arranged below said combustion chamber.
8. In an oil burner, the combination of a bottom body member open at the top and bottom, a top body member superimposed thereon and having a concentric combustion chamber wall depending from its upper edge providing a chamber open at the top and bottom, an inner wall comprising a bottom member 15 having a central restricted opening therein and provided with an annular fuel trough, an intermediate member mounted on said bottom member for rotative and vertical movement and having openings therein associated with 20 said bottom member so that they are normally closed, and a top member mounted on said intermediate member to permit independent rotative movement of such intermediate member, a cover plate mounted on said bottom inner wall member and coacting therewith to provide a bearing chamber, an annular fuel trough cover member operatively associated with said cover plate and intermediate wall member for independent rotative movement, 25 an atomizing head disposed within said combustion chamber, a spindle therefor arranged through said bearing member and provided with a bearing therein, a propeller arranged on said spindle within said bottom body member and below said inner wall bottom member, a nozzle arranged to deliver above said atomizing head, said combustion chamber and top inner wall member having openings to receive said nozzle, and fuel supply connections for said nozzle disposed within said top body member.
9. In an oil burner, the combination of a bottom body member open at the top and bottom, a top body member superimposed thereon and having a concentric combustion chamber wall depending from its upper edge providing a chamber open at the top and bottom, an inner wall comprising a bottom member having a central restricted opening therein and provided with an annular fuel trough, an intermediate member mounted on said bottom member for rotative and vertical movement and having openings therein associated with said bottom member so that they are normally closed, and a top member mounted on said intermediate member to permit independent rotative movement of such intermediate member, and a fuel feed means 30 disposed in said combustion chamber.
10. In an oil burner, the combination of a bottom body member open at the top and bottom, a top body member superimposed thereon and having a concentric combustion chamber wall depending from its upper edge providing a chamber open at the top and bottom, an inner wall comprising a bottom member having a central restricted opening therein and provided with an annular fuel trough, an intermediate member mounted on said bottom member for rotative and vertical movement and having openings therein associated with said bottom member so that they are normally closed, and a top member mounted on said intermediate member to permit independent rotative movement of such intermediate member, a cover plate mounted on said bottom inner wall member and coacting therewith to provide a bearing chamber, an annular fuel trough cover member operatively associated with said cover plate and intermediate wall member for independent rotative movement, and a fuel feed means 35 disposed in said combustion chamber.
11. In an oil burner, the combination of a bottom body member open at the top and bottom, a top body member superimposed thereon and having a concentric combustion chamber wall depending from its upper edge providing a chamber open at the top and bottom, an inner wall comprising a bottom member having a central restricted opening therein and provided with an annular fuel trough, an intermediate member mounted on said bottom member for rotative and vertical movement and having openings therein associated with said bottom member so that they are normally closed and a top member mounted on said intermediate member to permit independent rotative movement of such intermediate member, and a fuel feed means 40 disposed in said combustion chamber.
12. In an oil burner, the combination of a body open at the bottom and having a combustion chamber open at the top and bottom, an inner wall mounted within said body in spaced relation to the walls thereof and with its upper end projecting above the lower edge of the combustion chamber wall providing a return air passage delivering to the bottom of the combustion chamber, said inner wall having a bottom portion with a central restricted opening therein, a bearing chamber within said inner wall having a restricted opening in the top thereof, an atomizing head disposed within said combustion chamber 45 and ranged through said bottom member and pro-

above the plane of its lower edge, a spindle therefor provided with a bearing arranged in said bearing chamber, a propeller arranged on said spindle at the lower end of said body 5 to be driven by the air passing therethrough, a nozzle delivering to said atomizing head, and a conical guard disposed in said bearing chamber above said bearing and having a tubular portion projecting through the opening 10 at the upper end of the bearing chamber.

13. In an oil burner, the combination of a body open at the bottom and having a combustion chamber open at the top and bottom, an inner wall mounted within said body in 15 spaced relation to the walls thereof and with its upper end projecting above the lower edge of the combustion chamber wall providing a return air passage delivering to the bottom of the combustion chamber, said inner wall 20 having a bottom portion with a central restricted opening therein, a bearing chamber within said inner wall having a restricted opening in the top thereof, an atomized head disposed within said combustion chamber 25 above the plane of its lower edge, a spindle therefor provided with a bearing arranged in said bearing chamber, a propeller arranged on said spindle at the lower end of said body to be driven by the air passing therethrough, 30 and a nozzle delivering to said atomizing head.

14. In an oil burner, the combination of a bottom member open at the bottom and having a concentric combustion chamber wall 35 depending from its upper edge providing a combustion chamber open at the top and bottom, an inner wall disposed within said body in spaced relation to the walls thereof and with its upper end projecting above the 40 combustion chamber in concentric relation thereto providing a return air passage delivering to the bottom of the combustion chamber, there being a bearing chamber within said inner wall having restricted air passages 45 at the top and bottom thereof, an atomizing head disposed within said combustion chamber above the plane of its lower edge, and a spindle therefor provided with a bearing within said bearing chamber and with a propeller disposed below said bearing chamber 50 to be driven by the air passing thereto, said spindle having a bearing positioned in the air passage below said propeller.

15. In an oil burner, the combination of a body open at the bottom and having a combustion chamber open at the top and bottom disposed centrally therein, an inner wall mounted within said body in spaced relation to the walls thereof and with its upper end 55 embracing the combustion chamber providing a return air passage delivering to the bottom of the combustion chamber, a bearing chamber within said inner wall having a restricted air opening at the bottom and top thereof, an atomizing head disposed within 60 said combustion chamber, a spindle therefor provided with a bearing arranged in said bearing chamber and with a second bearing at the lower end of said body whereby a flow of air is secured around said bearings, a propeller arranged on said spindle below 65

within said combustion chamber, a spindle therefor provided with a bearing arranged in said bearing chamber, a propeller arranged on said spindle within the lower end of said body to be driven by the air passing therethrough, a nozzle delivering to said atomizing head, and a conical guard disposed in said bearing chamber above said bearing and having a tubular portion projecting through the opening at the upper end of the bearing 70 75 chamber.

16. In an oil burner, the combination of a body open at the bottom and having a combustion chamber open at the top and bottom disposed centrally therein, an inner wall 80 mounted within said body in spaced relation to the walls thereof and with its upper end embracing the combustion chamber providing a return air passage delivering to the bottom of the combustion chamber, a bearing chamber within said inner wall having a restricted air opening at the bottom and top thereof, an atomizing head disposed within said combustion chamber, a spindle therefor provided with a bearing arranged in said bearing chamber, a propeller arranged on said spindle within the lower end of said body to be driven by the air passing therethrough, and a nozzle delivering to said 85 atomizing head. 90 95

17. In an oil burner, the combination of a body open at the bottom and having a combustion chamber open at the top and bottom disposed centrally therein, an inner wall 100 mounted within said body in spaced relation to the walls thereof providing an air passage delivering to the bottom of the combustion chamber, a bearing chamber within said inner wall having a restricted air opening at the bottom and top thereof, an atomizing head disposed within said combustion chamber, a spindle therefor provided with a bearing arranged in said bearing chamber and with a bearing at the lower end of said body, and a nozzle delivering 105 to said atomizing head. 110

18. In an oil burner, the combination of a body open at the bottom and having a combustion chamber disposed centrally at its upper end, said combustion chamber being 115 open at the top and bottom, an inner wall disposed within said body in spaced relation to the walls thereof and with its upper end in a concentric relation to said combustion chamber providing a return air passage delivering 120 to the bottom of said combustion chamber, a centrally disposed bearing chamber having restricted air openings at the top and bottom thereof, an atomizing head disposed within said combustion chamber, a spindle therefor provided with a bearing arranged in said bearing chamber and with a second bearing 125 at the lower end of said body whereby a flow of air is secured around said bearings, a propeller arranged on said spindle below 130

said bearing chamber to be driven by the draft of air within said burner body, and a nozzle delivering to said atomizing head.

19. In an oil burner, the combination of a body open at the bottom and having a combustion chamber disposed centrally therein, said combustion chamber being open at the top and bottom, an inner wall disposed within said body in spaced relation to the walls thereof and with its upper end embracing the said combustion chamber providing a return air passage delivering to the bottom of the combustion chamber, an atomizing head disposed within said combustion chamber above the plane of the bottom thereof, a fuel nozzle delivering to said atomizing head, a spindle for said atomizing head provided with a bearing arranged adjacent to but below said atomizing head, a guard for said bearing having a tubular portion embracing said spindle, a propeller on said spindle, and means for bypassing a portion of the air at a point above said propeller through said bearing guard.
20. In an oil burner, the combination of a body member open at the bottom for the ingress of air, a combustion chamber disposed centrally within said body, said combustion chamber being open at the top and bottom, an inner wall disposed within said body in spaced relation to said combustion chamber and body walls providing an air passage delivering to the bottom of said combustion chamber, an atomizing head comprising an annular atomizing plate provided with fan blades, a rim disposed to embrace said atomizing plate and adjacent to said combustion chamber walls, a baffle plate disposed above and in spaced relation to said atomizing plate, a nozzle arranged to deliver to said atomizing plate, a spindle for said atomizing head, and a blade propeller mounted on said spindle within said air passage to be driven by the draft of air therethrough.
21. In an oil burner, the combination of a body member open at the bottom for the ingress of air, a combustion chamber disposed centrally within said body, said combustion chamber being open at the top and bottom, an inner wall disposed within said body in spaced relation to said combustion chamber and body walls providing an air passage delivering to the bottom of said combustion chamber, a rotatably mounted atomizing head comprising an annular atomizing plate provided with fan blades, a rim disposed to embrace said atomizing plate and adjacent to said combustion chamber walls, a baffle plate disposed above and in spaced relation to said atomizing plate, and a nozzle arranged to deliver to said atomizing plate.
22. In an oil burner, the combination of a body open at the bottom and having a combustion chamber disposed centrally therein, said combustion chamber being open at the top and bottom, an inner wall disposed within said body in spaced relation to the walls thereof and with its upper end disposed in concentric relation to said combustion chamber providing a return air passage delivering to the bottom of the combustion chamber, said combustion chamber and inner walls having aligned openings therein, an atomizing head comprising a top plate, radial arms mounted thereon in a plane below said top plate, an annular rim disposed on the outer ends of said arms, an annular atomizing plate disposed on said arms and provided with fan blades lying within the plane of said rim, and a fuel nozzle arranged through said openings in said walls to deliver upon said atomizing plate.
23. In an oil burner, the combination of a body open at the bottom and having a combustion chamber disposed centrally therein, said combustion chamber being open at the top and bottom, an inner wall disposed within said body in spaced relation to the walls thereof and with its upper end disposed in concentric relation to said combustion chamber providing a return air passage delivering to the bottom of the combustion chamber, an atomizing head comprising a top plate, radial arms mounted thereon in a plane below said top plate, an annular rim disposed on the outer ends of said arms, an annular atomizing plate disposed on said arms and provided with fan blades lying within the plane of said rim, and a fuel nozzle arranged through said openings in said walls to deliver upon said atomizing plate.
24. In an oil burner, the combination of a combustion chamber open at the top and bottom, an atomizing head rotatably mounted within said combustion chamber and comprising a centrally disposed baffle plate, radial arms projecting beyond said baffle plate in a plane below the same, an annular rim mounted on said arms, an annular atomizing plate disposed on said arms within said rim and provided with fan blades, and means for delivering liquid fuel upon said atomizing plate.
25. In an oil burner, the combination of a body open at the bottom and having a concentrically disposed combustion chamber wall depending from the top providing a combustion chamber open at the top and bottom, an inner wall mounted within said body in concentric relation to the walls thereof and of said combustion chamber wall providing a return air passage delivering to the bottom of the combustion chamber, an atomizing head rotatably mounted in said combustion chamber, a fuel nozzle comprising a downwardly inclined delivery tube, a tubular nozzle member slidably mounted thereon and having a downwardly directed delivery tip, a tubular casing embracing said nozzle member and having an enlargement at its upper end slidable on said delivery tube providing

an outer protecting casing and an overflow passage, said casing having a discharge opening at its inner end, said combustion chamber and inner wall having aligned openings therein to receive said nozzle and permit its sliding engagement with said delivery tube, said casing enlargement having a positioning lug thereon coacting with positioning lugs on said combustion chamber wall.

- 10 26. In an oil burner, the combination of a body open at the bottom and having a concentrically disposed combustion chamber wall depending from the top providing a combustion chamber open at the top and bottom, an inner wall mounted within said body in concentric relation to the walls thereof and of said combustion chamber wall providing a return air passage delivering to the bottom

of the combustion chamber, an atomizing head rotatably mounted in said combustion chamber, a fuel nozzle comprising a downwardly inclined delivery tube, a tubular nozzle member slidably mounted thereon, a tubular casing embracing said nozzle members providing an outer protecting casing and an overflow passage, said casing discharge having a discharge opening at its inner end, said combustion chamber and inner wall having aligned openings therein to receive said nozzle and permit its sliding engagement with said delivery tube.

In witness whereof we have hereunto set our hands.

EDWARD A. FIELD.

EDWARD A. FIELD, JR.
